Primary Examiner — Marie D. Fast Horse*Assistant Examiner* — Altaira J Swangin(74) *Attorney, Agent, or Firm* — Krishna Kalidindi(57) **CLAIM**

The ornamental design for a computer case as shown and described.

DESCRIPTION

FIG. 1 is a perspective view of a computer case showing the claimed design, the computer case being in a first configuration showing louvers in a closed state;

FIG. 2 is a front view of the computer case of FIG. 1, the computer case being in a second configuration showing the louvers in a partially open state;

FIG. 3 is a side view of the computer case of FIG. 1;

FIG. 4 is a top view of the computer case of FIG. 1; and,

FIG. 5 is a bottom view of the computer case of FIG. 1. Elements shown in dashed lines represent non-claimed portions of the computer case and form no part of the claimed design.

1 Claim, 4 Drawing Sheets(56)
